UNITED STATES PATENT OFFICE.

ALEXANDER M. GOW, OF DULUTH, MINNESOTA.

STEAM-SHOVEL DIPPER.

1,274,533.

Specification of Letters Patent.

Patented Aug. 6, 1918.

Application filed December 10, 1917. Serial No. 203,430.

To all whom it may concern:

Be it known that I, ALEXANDER M. Gow, a citizen of the United States, and resident of Duluth, in the county of St. Louis and State of Minnesota, have invented certain new and useful Improvements in Steam-Shovel Dippers, of which the following is a specification.

This invention relates to steam shovel dippers and more particularly to dipper fronts.

One of the objects of my invention is to improve and simplify dipper fronts to facilitate the efficient use thereof.

Another object is to improve the connection of teeth to dipper fronts to facilitate their removal and replacement, and also to prevent lateral movement of the teeth when fixed in place.

Generally speaking, these and other objects are accomplished by providing a dipper front comprising a wall having recesses on the inside and outside for the reception of a bifurcated tooth, the walls of the recess preventing lateral movement of the tooth.

The invention is illustrated on the accompanying sheet of drawings in which,

Figure 1 is a top plan view of the dipper front;

Fig. 2 is a front elevation of the same;

Fig. 3 is a side elevation of the dipper front parts being in section to show the connection between the front wall of the dipper and one of the teeth; and

Fig. 4 is a detail sectional view on an enlarged scale showing the connection between the dipper front and tooth.

At present it is customary to forge teeth with large shanks which extend into the dipper on the inside. Another construction is to cast the shank integral with the dipper front. In either case spaces are left between the shanks of the teeth on the inside of the dipper, and these spaces fill up with dirt and ice reducing the capacity of the dipper and preventing the free ingress and egress of the material. In my improved dipper front the inside of the dipper is practically smooth, while I make provision on the outside for any reinforcing or strengthening that may be necessary.

By referring to the figures of the drawings, it will be noted that I have shown a dipper front 10 having a front wall 11 and side walls 12 and 13, the front wall being

somewhat curved. Formed integrally with this front are a plurality of strengthening ribs 14 which are located on the outside of the front. The front portion of each of the ribs is provided with a recess 15 which widens toward the upper end of the front. The inside of the front also is provided with an oppositely arranged duplicate recess 16, the two recesses in each case forming a tongue 17 which tapers outwardly and fits into the bifurcated portion of the tooth 18. The upper ends of the duplicate recesses 15 and 16 terminate in a notch 19, or it might be said that a U-shaped recess is provided for the reception of each tooth 18. The side walls 20 and 21 of each recess coöperate to prevent lateral movement of the teeth when the same are set in place. To securely fasten the teeth to the dipper front, rivets 22 or their equivalent are passed through registering openings in the bifurcated end of the teeth and the associated tongues 17 formed by the recesses 15 and 16. The recesses 15 and 16 at their lower extremities, terminate in shoulders 23 against which the ends of the bifurcated portion of the teeth 18 abut, and in view of the fact that the exterior of the bifurcated portions of the teeth are flush with the coöoperating rib portions a smooth surface is provided to facilitate the operation of the dipper.

In view of the fact that the dipper front is curved or concave on the inside, the outer recess 15 in each case is located at a greater distance from the center line of the front than the inside recess 16 in each case. It will be noted also that the outside recess 15 projects farther from the surface of the front than the inside recess does and that the rib on the outside is in alinement with the recess to act as a runner to protect the front.

By means of this arrangement, teeth may be reversed thereby prolonging the life of the teeth without reforging the same. These teeth are easily removed and replaced. The same are held against lateral movement when set in place and at the same time the dipper front is provided with the desirable smooth inside surface.

It is my intention to cover all modifications which come within the spirit and scope of the following claim.

What I claim is:

A dipper having a rib on the exterior of the front thereof, said rib having a longi-

tudinal recess extending to the top of the front and around the upper edge thereof and into the inner side of the front of the dipper, the recess being continuous from the exterior to the interior of the front, uniform, and of U shape to form a solid tongue having lateral shoulders, a reversible tooth having jaws to receive said tongue, said jaws being

confined between the shoulders, and means for securing the tooth in place. 12

Signed at Duluth, Minn., this 5th day of December, A. D. 1917.

ALEXANDER M. GOW.
